REMOTE CONTROL SYSTEM

Willard P. Place, Penn Township, Allegheny County, Pa., assignor to The Union Switch & Signal Company, Swissvale, Pa., a corporation of Pennsylvania

Application December 17, 1943, Serial No. 514,642

5 Claims. (CL. 177—353)

1

My invention relates to remote control systems, and more particularly to centralized traffic control systems for railroads for the control of railway signals or other traffic controlling devices from a central point of control, such as a train dispatcher's office, and for the indication of such devices or of train movements at the control office.

One object of my invention is the provision of a system of remote control suitable for the direct control of unattended manual block signals. The system of my invention is an improvement upon that disclosed in a copending application for Letters Patent of the United States, Serial No. 514,641, filed December 17, 1943, now U. S. Letters Patent 2,396,134 granted March 5, 1946, by Andrew J. Sorenson, for Remote control system.

Another object of my invention is the provision of a system for communicating by code between a control office and a plurality of remote stations, in which the codes comprise single impulses of alternating current within a band of frequencies which is preferably above the voice frequency range but suitable for transmission over existing telephone circuits, the current being modulated at different rates, and in which the modulating frequencies are applied singly or sequentially to provide code signals of different characters.

Other objects, features and purposes of my invention will be pointed out as the description proceeds.

I shall describe one form of apparatus embodying my invention, and shall then point out the novel features thereof in claims.

Referring to the accompanying drawing, the reference characters Y and Z designate a pair of line wires which it is to be understood provide a telephone circuit extending from a control office at which the apparatus at the left of the drawing is located, through a plurality of stations situated at spaced points along a stretch of railway at each of which stations a pair of manual block signals LH and RH is provided, as indicated by the track diagram, each station being equipped with apparatus similar to that shown at the right of the drawing having a connection to the line wires Y and Z as shown. It may be assumed that the stretch is not provided with track circuits except for a short detector section at each station, each such section having a track relay TR for controlling the signals and for indicating the movements of trains past the station, train movements through the stretch being governed

2

primarily by train orders supplemented by manual control of the signals.

The signals, identified by the references LH and RH, are of the usual color light type, arranged to display proceed, permissive or stop indications by the lighting of suitable lamps G, Y and R, respectively, the circuits for which are controlled by a group of stick relays DS, LHS and RHS.

In its specific embodiment as shown, the system of my invention provides facilities for the manual control of such a group of signal control relays at each of five stations and for indicating at the office the positions of relays LHS and RHS at each station. The control apparatus at the office comprises a control panel for each station, each including one of a series of push-buttons PB1 to PB5. Each button when pressed effects the delivery of alternating current of a distinctive frequency to the line circuit to which the apparatus at the corresponding station is selectively responsive, and this current is modulated at different rates in accordance with the positions of a pair of signal levers such as HLI and DLI in the corresponding panel to selectively control the relays DS, LHS and RHS at the selected station. More particularly, the momentary operation of one of the five buttons PB1 to PB5 effects the delivery of an impulse of modulated carrier current to the line wires Y and Z having a frequency identified as f11 to f15, respectively, which is modulated at a frequency identified as f1, f2 or f3, thereby energizing the corresponding one of the three relays DS, LHS or RHS at the selected station. A group of three relays M1, M2 and M3 provides means whereby the carrier current may be modulated at any one of the three frequencies f1, f2 or f3, and also serves to apply the frequencies f1 and f2 or f1 and f3 alternately so that relay DS may be picked up along with relay LHS or RHS. Relays LHS and RHS are slow release relays which are held picked up by local stick circuits controlled by the track relay TR, while relay DS is held energized by a local stick circuit controlled by relay LHS or RHS. A quick acting relay MP, which responds to each of the modulation frequencies f1, f2 and f3 is operated by each control impulse of modulated carrier current having the carrier frequency to which the station is selectively responsive, and provides means for manually releasing the signal stick relays, and for energizing an indication transmitter relay T1 in response to each control impulse received.

55 The following table lists the relays M which

are energized, the modulation frequencies of the control impulses, the control relays at the selected station which are energized, and the signal lamps which are lighted in response to the control impulses, for each of the different operating positions of the signal levers HL1 and DL1:

Levers		Modulation		Control Relays	Signals	
HL1	DL1	Relays	Frequency		RH	LH
Center	Left	M1	f1	DS	R	R
Right	do	M3	f3	RHS	Y	R
Do	Right	M3, M1	f3, f1	RHS, DS	G	R
Left	Left	M2	f2	LHS	R	Y
Do	Right	M2, M1	f2, f1	LHS, DS	R	G

Relay T1 is a slow release relay, and it is arranged to be energized momentarily when a train enters the detector track section to put the signals automatically to stop. The energization of relay T1 effects the delivery of an indication impulse of modulated carrier current to the line wires Y and Z having a frequency which is characteristic of the station, the carrier frequencies transmitted from the five different stations being identified as f16 to f20, respectively. This current is modulated at a frequency f1 if relays LHS and RHS are released and at a frequency f2 if one of these relays is energized, and serves to operate an office indication relay K of the stick polar type selected by the carrier frequency and controlling one of a series of lamps E1-E5 to indicate the condition of the signals at the transmitting station. Lamp E1, for example, responds to the frequency f16 and is lighted only when the signals at the station shown are at stop.

To generate the impulses employed for the control of the signals, an oscillator comprising an electron tube VT1 is provided at the office which is arranged to generate carrier currents of different frequencies by the provision of an adjustable tuned circuit including the coil 21 and a plurality of condensers such as C1. In the drawing, various tuned circuits are shown comprising coils and condensers arranged to respond selectively to particular frequencies, and to enable the operation of the system to be more readily understood, a legend indicating the frequency to which the circuit is responsive is shown adjacent the tuned circuit elements in each instance. The connections to coil 21, for example, are such that the electron tube VT1 may be adjustably connected so as to generate any one of the five control frequencies f11 to f15. These frequencies are modulated by a second electron tube VT2 having a control circuit including a tuning coil 22 and a condenser such as C2 by means of which the tube VT2 may be adjustably connected so as to generate any one of three modulation frequencies f1, f2 or f3, which frequencies are impressed upon the input circuit for the tube VT1 so as to cause periodic variations in the amplitude of the current of the carrier frequency delivered thereby. The modulated carrier currents are delivered to the line wires Y and Z through an amplifier tube VT3 and a band pass filter f11-15 and received through a similar filter at each station and supplied to the input circuit of an amplifier tube VT8.

The indication impulses transmitted from each station comprise modulated carrier currents generated by electron tubes similar to those at the office, these including a tube VT5 for generating one of five carrier frequencies in a band f16-20, such as the frequency f16, as shown, and a tube

VT6 for generating either of two modulation frequencies f1 and f2. The modulated carrier current generated by these tubes is delivered to the line wires Y and Z through an amplifier tube VT7 and a band pass filter f16-20, and supplied through a similar filter at the office to the input circuit of an amplifier tube VT4.

It is to be understood that the band pass filters f11-15 and f16-20 are arranged to present a relatively low attenuation to currents of the designated carrier frequencies as well as to the side band frequencies associated therewith, and that the filters f11-15 present a maximum attenuation to frequencies passed by the filters f16-20, and vice versa.

I shall now describe the operation of the system of my invention in detail, assuming first that the operator moves lever HL1 to its right-hand position and then presses the associated push-button PB1, in order to light lamp Y of signal RH at the station shown.

The filament circuits for the electron tubes at the office and at each station are normally energized by connections to the terminals B and C of a suitable low voltage source, while their plate circuits are energized from a high voltage source having the terminals BH and C. The connections for energizing the plate circuits for tubes VT1, VT2 and VT3 include the contacts b of the push-buttons PB, and the closing of contact b of button PB1 therefore activates the electron tubes VT1, VT2 and VT3, while the closing of contact c of button PB1 completes a tuned circuit including coil 21 and a condenser C1, resonant to the frequency f11, causing tube VT1 to generate that frequency. The closing of contact a of button PB1 completes a circuit from terminal B of the local low voltage source over the right-hand contact a of lever HL1, back contact c of relay M1 through relay M3 to terminal C, so that relay M3 becomes energized completing a tuned circuit at its front contact b including a portion of the coil 22 and a condenser similar to C2, which circuit is resonant to the frequency f3, causing tube VT2 to generate that frequency and to modulate the carrier current of frequency f11 at the corresponding rate. This modulated current is delivered to the line by the amplifier VT3 and received by the amplifier VT8 at each of the stations, where the output of the tube VT8 is supplied to a rectifier 23 through a two-stage filter tuned to a different frequency at each station, and arranged to pass only one of the carrier frequencies of the band f11-15 together with the side band frequencies corresponding to its modulation, this carrier frequency being f11 at the station shown. Rectifier 23 therefore receives the carrier current of frequency f11 at the one station only, and serves as a detector or demodulator to convert its periodic variations into alternating current, which in the case being described is of frequency f3. This alternating current is supplied to three sets of tuned circuit elements which provide resonant circuits selectively responsive to the frequencies f1, f2 and f3, respectively, each comprising a condenser such as C3 and a coil 28 to which the input terminals of a rectifier 25 are connected, the output terminals of each rectifier 25 being connected to one of the relays DS, LHS and RHS. Each resonant circuit is completed through a rectifier 24 and relay MP, and through rectifier 23 and resistor 29, in parallel. Since the frequency supplied is f3, it will be seen that relay RHS becomes energized through rectifier 25, and relay MP through rectifier 24, due to the

resonant response of the circuit elements tuned to that frequency.

When button PB1 is released to terminate the control impulse, relay MP releases quickly, completing a stick circuit for relay RHS extending from terminal B at front contact *a* of relay TR, back contact *a* of relay MP, and the front contact *a* and winding of relay RHS to terminal C, so that relay RHS remains picked up lighting lamp Y and extinguishing lamp R of signal RH by the operation of its contacts *c* and *b*.

When relay MP picks up, the closing of its contact *b* energizes relay T1 which closes its contact *a* and thereby connects terminal BH of the high voltage source at the station to the plate circuits for tubes VT5, VT6 and VT1. Tube VT5 is adjustably connected to generate carrier current of frequency f_{16} only, modulated by tube VT6, and when relay RHS picks up its contact *f* shifts the connections to coil 26 to change the modulation frequency from f_1 to f_2 , consequently current of frequency F_{16} generated by tube VT5 and modulated at the frequency F_2 by the electron tube VT6 is supplied to the line until relay T1 releases, following the release of relay MP. At the office, this current is received by the amplifier tube VT4 and supplied to five similar sets of selective circuit elements, of which but two are shown, each responsive to a different one of the five frequencies f_{16} to f_{20} , to each of which is connected a demodulator 27 for supplying current of frequency f_1 or f_2 to two tuned circuits selectively responsive to these frequencies and similar to those controlling relays DS and LHS but arranged to operate a polar stick relay such as the relay K1 to its normal or reverse position. In the case being described, the carrier frequency is f_{16} and the modulation frequency is f_2 , and consequently relay K1 reverses to extinguish lamp E1, thereby indicating the response of relay RHS to the operation of button PB1.

I shall next assume that the operator moves lever DL1 to the right, leaving lever HL1 in its right-hand position, and then presses button PB1, in order to light lamp G of signal RH at the station shown.

In response to the operation of button PB1, relay M3 becomes energized and the electron tubes VT1, VT2 and VT3 become activated to deliver current of frequency f_{11} modulated at the frequency f_3 to the line, as the preceding example, and in addition, a circuit is completed from terminal B at contact *a* of button PB1 over the right-hand contact *a* of lever HL, front contact *a* of relay M3 and the right-hand contact *a* of lever DL through relay M1 to terminal C, so that relay M1 picks up. The opening of back contact *c* of relay M1 deenergized relay M3, which therefore releases after a brief period, the dropping of its contacts *a* and *b* opening the circuit for relay M1 and changing the modulation frequency to f_1 by completing the tuned circuit including back contacts *b* of relay M3 and M2 and front contact *b* of relay M1. Relay M1 releases after a brief period, and by closing its back contact *c*, reenergizes relay M3 which operations change the modulation frequency from f_1 to f_3 . Relay M3 reenergizes relay M1 again, these operations continuing as long as button PB1 is held pressed, so that the carrier current is modulated alternately and repeatedly by the frequencies f_1 and f_3 , at a rate sufficient to maintain relay RHS picked up and also energizing relay DS to complete its stick circuit extending to terminal B at the front contact *d* of relay RHS.

Consequently, when button PB1 is released, relays RHS and DS remain energized to light lamp G of signal RH. The resultant indication impulse is similar to that previously described and consequently lamp E1 remains dark.

Signal LH may be similarly caused to display its permissive indication by operating lever HL1 to the left, with lever DL1 in its normal left-hand position, in which case the modulation frequency is f_2 instead of f_3 , while if lever DL1 is in its reversed or right-hand position, the frequencies f_1 and f_2 are applied alternately by the operation of relays M1 and M2 to pick up relay DS along with relay LHS, thereby causing signal LH to indicate proceed.

I shall next assume that after signal LH or RH has been cleared, that the operator restores the signal levers to their normal positions as shown in the drawing, and then presses button PB1 to put the cleared signal to stop. Relay M1 picks up, causing the frequency f_{11} delivered to the line in response to the operation of button PB1 to be modulated by the frequency f_1 , thereby energizing relays DS and MP. The opening of contact *a* of relay MP releases relay LHS or RHS, thereby putting the signal to stop and opening the stick circuit for relay DS, so that when the impulse is terminated, relay DS releases along with relay MP. An indication impulse of frequency f_{16} is transmitted to the office as in the preceding example, but in this case it is modulated by the frequency f_1 , because relays LHS and RHS are both in their released positions, thereby energizing relay K1 in the normal direction to light lamp E1 to indicate that the previously cleared signal has been restored to stop.

When a train enters the detector track section to release relay TR, with signal LH or RH displaying its permissive or clear indication, relay LHS or RHS is deenergized to restore the signal automatically to stop, due to the opening of front contact *a* of relay TR, but before the relay LHS or RHS releases, a circuit is closed momentarily from terminal B over back contact *a* of relay TR and front contact *a* of relay LHS or RHS to pick up relay T1, causing the transmission of an indication impulse which will be modulated by the frequency f_1 when both relays LHS and RHS are in their released positions, to light lamp E1, as in the preceding example, thereby indicating the movement of the train into the detector section and the return of the signal to stop.

If a different station selecting push-button, such as the button PB5, is operated, similar operations will be effected at another station at which the apparatus is responsive to another carrier frequency, such as f_{15} , the resulting indication impulse also having a different carrier frequency, such as f_{20} , to control an indication relay K5, as will be readily understood.

It may happen that a control impulse is being transmitted to one station, and an indication impulse received from that station at the time a train enters the detector track section at another station and initiates the transmission of another indication impulse. No interference will occur, and the various indication relays K1 to K5 may be operated simultaneously due to the provision of communication channels between the office and different stations which are selectively responsive to different carrier frequencies as described.

Although I have herein shown and described only one form of remote control apparatus em-

bodying my invention, it is understood that various changes and modifications may be made therein within the scope of the appended claims without departing from the spirit and scope of my invention.

Having thus described my invention, what I claim is:

1. In a remote control system, an office and a station connected by line wires, manually controllable means for at times impressing carrier current of a given carrier frequency on the line wires and for selectively modulating said current by different modulation frequencies, means at the station for selectively receiving said current including selective circuit elements resonant to the carrier frequency, demodulating means for converting said current to alternating current of the modulation frequency, a group of slow release control relays at said station, circuits for selectively controlling said relays by the alternating current supplied by said demodulating means, the circuit for each control relay including a rectifier and selective circuit elements resonant to a different one of said modulation frequencies, a quick release relay, an energizing circuit for said quick release relay including a rectifier interposed in the circuits by which said demodulating means supplies current to said selective circuit elements, and rendering such relay responsive to current of any of said modulation frequencies, a holding circuit for each control relay including its own front contact and a back contact of said quick release relay, a slow release transmitter relay controlled by a front contact of said quick release relay, means controlled by said transmitter relay when energized for impressing carrier current of a second carrier frequency on the line wires and for modulating such current by different modulation frequencies in accordance with the condition of said control relays, means at the office for selectively receiving said second carrier current including selective circuit elements resonant thereto, demodulating means for converting said second carrier current to alternating current of the modulation frequency, and an indication relay controlled thereby for indicating the condition of said control relays.

2. In a remote control system, a slow release stick relay and a second stick relay, a plurality of control circuits governed jointly by said relays, pick-up circuits for said relays including rectifiers supplied with current through resonant circuit elements to render each relay responsive to alternating current of a different frequency, quick acting relay connected through a rectifier to said resonant circuit elements to render such relay responsive to current of each of said different frequencies, holding circuits for said stick relays including their own front contacts, that for the slow release relay including a back contact of said quick acting relay and that for the second stick relay including a front contact of said slow release relay, means for supplying an impulse of alternating current of one of said frequencies or the other to said selective circuit elements whereby the slow release relay is picked up to be held energized upon the release of said quick acting relay or is released in response to the operation of said quick acting relay, and means for supplying impulses of the different frequencies to said circuit elements in quick succession whereby the stick circuit for the second stick relay is completed and both stick relays are

held energized upon the release of said quick acting relay.

3. In a remote control system, three stick relays, two of which are slow to release, a plurality of control circuits governed jointly by said relays, pick-up circuits for said relays including rectifiers supplied with current through resonant circuit elements to render each relay responsive to alternating current of a different one of three frequencies, a quick acting relay connected through a rectifier to said resonant circuit elements to render such relay responsive to current of any one of said three frequencies, holding circuits for the two slow release stick relays including a back contact of said quick acting relay, a holding circuit for the third stick relay including front contacts of said two slow release stick relays connected in parallel, means for supplying impulses of alternating current of said three different frequencies to said resonant circuit elements one frequency at a time whereby one slow release relay or the other is picked up to be held energized upon the release of said quick acting relay or is released by the operation of said quick acting relay, and means for supplying impulses of two frequencies to said circuit elements in quick succession whereby the stick circuit for said third stick relay is completed to hold such relay energized along with one or the other of said slow release relays following the release of said quick acting relay.

4. In a remote control system, an office and a plurality of stations connected by line wires, a controllable device and a locally controlled relay at each station, a stick relay at each station for governing the controllable device at such station, a stick circuit for each stick relay including a front contact of the associated locally controlled relay, manually operable means at the office for controlling said stick relay, transmitting means at each station responsive to the release of the locally controlled relay for impressing upon the line wires an impulse of alternating carrier current, the transmitting means at different stations being adapted to transmit impulses of different carrier frequencies, means at each station for modulating the carrier current impressed upon the line wires by the associated transmitting means by one frequency or another dependent upon the position of the associated stick relay, indication means at the office for indicating the positions of said stick relays, and circuits for controlling said indication means including selective circuit elements resonant to each of said carrier frequencies and other selective circuit elements resonant to each of said modulation frequencies.

5. In a remote control system, an office and a station connected by line wires, means at the office for impressing alternating carrier current on the line wires, means for modulating said current at one or another selected frequency, control means for selecting the modulation frequency, means at the station for selectively receiving said current including selective circuit elements resonant to the carrier frequency together with means for converting said current to alternating current of the modulation frequency, a slow release stick relay, a second stick relay, a quick acting relay, and control means controlled jointly by said stick relays, all located at the station, a circuit for controlling each stick relay and said quick acting relay by said alternating current each said circuit including a rectifier and selective circuit elements resonant to an impulse of a

different modulation frequency whereby each stick relay may be operated along with said quick acting relay without operating the other, a holding circuit for said slow acting stick relay governed by a back contact of said quick acting relay to maintain the slow acting relay energized following the reception of an impulse of a given frequency and to release such relay upon the reception of an impulse of a different frequency, a holding circuit for said second stick relay including a front contact of said slow acting relay, and means for operating said control means periodically to supply impulses of two modulation frequencies alternately and repeatedly and thereby operate said second stick relay without releasing said slow acting relay.
